WELL HEAD ASSEMBLY

Arthur J. Penick and Kirby T. Penick,
Houston, Tex.

Application April 20, 1931, Serial No. 531,348

6 Claims. (Cl. 166—14)

The invention relates to an improvement in well head assemblies wherein complete control of the flow of fluid from the casing and from the tubing may be maintained at all times.

5 In flowing the fluid from oil wells it is often desirable to completely close off the well in order to make repairs or alterations in the flow lines or valves. As now practiced the tubing in the well extends upwardly from the casing and is connected with what has been designated as the Christmas tree, which comprises the branch lines, valves, pressure gauges and other instruments and fixtures which are desirable about the well. If, however, any of these fixtures or fittings be- 10 come disabled through wear or accident it is practically impossible to cut off the flow of fluid in order to make repairs. The present invention has therefore been devised with the idea in view of so arranging the fittings that the flow from the 15 well can be completely closed off and proper and suitable repairs made to the fittings on the well head as desired.

One of the objects of the invention is to provide a well head assembly wherein the tubing is supported in a hanger below the gate valve and wherein the Christmas tree fittings above the valve are swiveled to the valve so that they may be aligned or repositioned as desired.

Another object of the invention is to provide a 20 tubing hanger and support therefor so that a seal may be obtained by means of steel to steel ground joint about the hanger when it is locked in position so that there will be no flow of fluid from inside of the casing to any point above the tubing 25 hanger.

Another object of the invention is to provide in combination with a tubing hanger a locking mechanism so that the hanger will be fixed in position to form a seal without flexible packing for 30 the casing head gas.

Another object of the invention is to provide in combination with a gate valve a Christmas tree assembly which is adapted for circumferential adjustment with respect to the gate valve and 35 which may be anchored in any desired adjusted position.

A still further object of the invention is to provide in combination with a well head assembly a gate valve which serves as a connection between 40 the tubing disposed above and below such valve.

A still further object is to provide a gate valve which will serve as a sand trap in the string of tubing.

A still further object of the invention is to provide pressure gauges in connection with the cas-

ing head and the tubing head so that the pressure in each of these members may be accurately determined.

Another object is to provide a gate valve which is so disposed that tubing may be attached above and below the valve so that the flow from the casing may be taken off below the valve and the flow from the tubing taken off above the valve.

Other and further objects of the invention will be readily apparent when the following description is considered in connection with the accompanying drawing wherein:

The drawing illustrates a side elevation of the well head assembly with certain portions shown in section to illustrate the internal construction thereof.

Another and further object of the invention is to provide a tubing head that eliminates all metallic packing making so that the head will safely withstand high temperatures in case of fire.

Another and further object of the invention is to provide a tubing head that permits the closing of the master gate with the tubing in the well bore without making any adjustments to head.

The well casing is illustrated at 2 and may be 40 of any desired diameter and is the casing which extends upwardly from the well and is usually anchored to the earth by cementing or otherwise. A coupling 3 is illustrated as being connected to the casing and arranged to receive the hanger head 4 or support head 4. This hanger head may be threaded internally for connection to the casing if desired or threaded externally to receive the coupling 3, as shown in the drawing. Extending from this head 4 is a flow line 5, which is provided with a valve 6. This flow line may be used during the drilling operation as an exit for the flushing fluid or for other purposes and is connected to the hanger head by threading into the 45 vent 7. A similar vent 8 is provided on the opposite side of the hanger head and is here illustrated as being closed by the bull plug 9. A second flow line may be connected to this vent 8, if desired. The bull plug 9 is shown as having been provided with a gauge 10, so that the pressure 50 inside of the casing or what is known as the casing head pressure may be determined. A valve 11 is shown on the bull plug in order to control the operation of the valve 10 and this valve may be closed so that it will serve to cut off the gauge 55 in event the gauge is to be removed or replaced.

The hanger head 4 is also constructed with an annular guide 14 projecting inwardly below the inclined seat 15 for the hanger 17. Said guide is engaged by the tubing and holds the collar 110

- thereon away from the seat 15 thus avoiding scoring or marring the seat, and thus assuring a seal at that point. The seat 15 is preferably ground and annular in configuration so that the hanger 5 17, which is provided with a tapered shoulder 20, may form a seal and seat upon this inclined face 15. The seal is necessary to prevent the passage of fluid, and the casing is thus entirely closed off at this point. Thus, the packing rings ordinarily 10 required, are entirely eliminated and are not present to be destroyed by fire or become otherwise unserviceable. It is intended that the weight of the tubing 18 will retain the hanger 17 in position but if desired a locking ring 21 may be provided and is so positioned above the hanger 17 that it will serve as an anchoring means or locking cap to hold the hanger against the seat and maintain a seal to prevent escape of gas from the casing. This ring or lock 21 is threaded into 15 the upper end of the head 4 so that it may be turned and screwed downwardly against the upper end of the hanger 17 to firmly retain it in position. Said ring 21 is provided with a plurality of openings 22 to receive a spanner wrench 20 or other tool so that it may be placed in position or removed therefrom by manipulation of the wrench through the gate valve 23, which is positioned above the hanger head. Another feature of advantage of the locking 25 ring 21 is the fact that in event the tubing should part at any elevation below the hanger, the locking ring would then hold the hanger in position. Thus if the tubing parted and sufficient pressure were present in the casing to lift the hanger 17 30 and any tubing connected to it, then the hanger might be moved upwardly into the valve housing and prevent closing of the valve. However, if the locking ring 21 is present any movement of the hanger is prevented. 35 The tubing hanger 17 is provided with two sets of threads 24 and 25. These threads are similar but of different diameter in order to receive two diameters of tubing. Above the threads 24 in the center of the hanger is a third set of threads 26 40 which are adapted to receive a piece of pipe or setting tool whereby the hanger and the string of tubing 18 may be set in the hanger head or removed therefrom by passing them through the gate valve 23. 45 The gate valve 23 is of usual construction and includes the gate which is manipulated by operation of the handle 29 to close the passage 30 through the body 31 of the valve. The valve is attached to the hanger head 4 by threading or 50 connection thereto as at 31 and is arranged to receive on the upper side thereof a support structure or nipple 32. The fittings above the gate valve are preferably supported on this adapter or support structure 32, which may be flanged 55 or threaded to the gate valve. The drawing illustrates this adapter as threaded at 33 to the valve and serving as a closure for the upper portion of the valve except for the outlet 34 through the upper end of the adapter. 60 Disposed above this adapter is the Christmas tree assembly 35, which includes the cross 36 flow lines 37, 38 and 39, each of which is provided with a valve 40. During the operation of the oil well and removal of the fluid therefrom 65 it often occurs that these flow lines and valves become disabled due to wear on the valve member caused by high pressure of the fluid and abrasives carried by this fluid. Often articles come in contact with the lines and the valves so 70 that they are accidentally broken or injured and 75

it becomes necessary to replace them or to re-assemble the lines when different conditions arise. It is, therefore, desirable to cut off the flow of fluid from this Christmas tree assembly by means of manipulation of a single member. With the present arrangement and assembly of the parts it is only necessary to close the gate of the valve 23 to completely cut off the flow of fluid to the Christmas tree assembly 35. This is accomplished due to the fact that the tubing 18 terminates at the lower side of the gate valve. The connection of the Christmas tree and the gate valve is made by a nipple as at 41. This continuation or nipple is adapted to be supported above the gate valve on the adapter 32 by means of a swivel connection 42. 80 85 90

This swivel connection is provided so that the cross 36 or the entire Christmas tree assembly may be moved circumferentially for the purposes of adjustment or to align the flow lines in such a position that repairs or alterations may be made. 95

The swivel 42 comprises a body 43, which is flanged at 44 in order to form a shoulder 45. This shoulder in turn receives the clamping plate 100 46, which is of such size that it will pass over the body 43 and engage the shoulder 45. Suitable anchor bolts 47 pass through the plate and are threaded into the nipple 32. Below the body 43 a pressure ring 48 is positioned in such a 105 manner that its upper and lower edges extend respectively into groove 49 in the bottom of the swivel body 43 and into the groove 50 in the top of the adapter or support structure 32. With this arrangement it is possible to adjust the bolts 110 47 so that the clamping plate 46 will be loosened and permit circumferential adjustment of the cross 35, the tubing section 41 and the swivel body 43. When the proper adjustment has been obtained the bolts are again screwed downwardly 115 to bring the clamping plate into locking position so that the swivel will be held in fixed position and a seal maintained about the upper end of the nipple 32. With this particular type of swivel it is possible to adjust the Christmas tree without entirely removing the same and by merely loosening the nuts holding the plates 46 in position. If it is desired to make alterations in the fittings or lines of the Christmas tree the handle 29 of the valve 23 may be rotated to close 120 125 the gate and shut off the entire Christmas tree assembly from the well. 130

This arrangement of the device eliminates the necessity of removing the tubing or separating the tubing in order to close the gate valve 130 and facilitates materially the closing of the gate valve in event of emergency. The gate valve, the support head and the casing may be used during the drilling operation and when the drilling of the well is completed and it is desired 135 to set tubing the tubing may be passed into the well with the hanger 17 positioned on the uppermost section of tubing. The hanger is passed into the well by connecting a section of pipe or setting tool to the threads 26. When the hanger 140 has been seated on the shoulders 15 or 16 the setting tool is then removed and the locking ring 21 is passed in through the gate valve and screwed into position to latch the hanger on its seat. The nipple 32 may then be placed in position and 145 this Christmas tree assembly connected thereto by means of the swivel 42. In event repairs or excessive pressure are encountered the valve 23 may be closed and, by manipulation of the valve 6, the pressure may be materially reduced in the 150

well and the flow line again opened. It will be seen that an advantage is obtained by the seal of the hanger with the hanger head because this eliminates much casing head pressure from passing into the gate valve and also eliminates any accumulation of sand or other material in the gate valve housing except such abrasive as may flow upwardly with the oil. The gate valve 23 serves as a sand trap for small amounts of abrasive and in this manner reduces the cutting action on the valves 40 and the other fittings of the Christmas tree. The present assembly eliminates the use of tubing separators and gate valves on the casing and tubing as the single valve 23 serves to cut off the entire flow from the well when considered in combination with the valve 6 on the flow line extending from the hanger head.

What we claim is:

20 1. A well head assembly including a casing, a gate valve thereon, a string of tubing suspended below said valve, an upper string of tubing supported above and upon said valve, a sealed swivel joint connecting said upper string of tubing to said valve to allow relative rotation without longitudinal movement, said valve being adapted to serve as the connection between said two strings of tubing.

25 2. The combination with a gate valve in a well head assembly, of an adapter connected thereto, a nipple, and a non-threaded swivel connection between said adapter and nipple whereby rotation of said nipple with respect to said valve may be had, said nipple being fixed to said swivel connection.

3. In a well head assembly the combination with a gate valve, of a Christmas tree assembly supported thereabove, a tubing suspended below said valve, and swivel means connecting said Christmas tree assembly to said valve whereby said assembly may be turned without axial movement to make flow line connections.

4. In a well head assembly the combination with a gate valve, of a tubing supported thereabove, a tubing suspended below said valve, a sealed swivel joint connecting said supported tubing to said valve, adapted to permit relative rotation without longitudinal displacement, and additional means to lock said suspended tubing in position.

5. The combination of a gate valve, Christmas tree assembly, and means connecting said valve and assembly including a swivel whereby said assembly may be adjusted circumferentially without longitudinal movement and fixed in such adjusted position.

6. In a well head assembly, the combination with a casing, of a support head on said casing, a sealing seat in said head adapted to receive and support a tubing hanger, a tubing hanger thereon, and means to anchor said tubing hanger against vertical displacement; a gate valve mounted above said support head, and a swivel connection above said valve, said swivel permitting rotation without axial displacement of the fittings located above and attached thereto.
